DESIGN FOR AN AMUSEMENT DEVICE

Harry E. Anderson, Belmont, Mass.

Application April 27, 1944, Serial No. 113,383

Term of patent 7 years

(Cl. D34—5)

To all whom it may concern:

Be it known that I, Harry E. Anderson, a citizen of the United States, residing at Belmont, in the county of Middlesex and State of Massachusetts, have invented a new, original, and ornamental Design for an Amusement Device, of which the following is a specification, reference being had to the accompanying drawings forming a part thereof, in which:

Figure 1 is a perspective view looking at the

front of the device from an angle of approximately 45 degrees.

Figure 2 is a perspective view looking at the device in the position to show the front and side as viewed from an angle of approximately 45 degrees from the horizontal.

I claim:

The ornamental design for an amusement device, as shown.

HARRY E. ANDERSON.
